(57) **CLAIM**

The ornamental design for a monitor, as shown and described.

DESCRIPTION

FIG. 1 is a front perspective view of a monitor, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is an enlarged view of the encircled portion 9 in FIG. 1;

FIG. 10 is an enlarged view of the encircled portion 10 in FIG. 1;

FIG. 11 is an enlarged view of the encircled portion 11 in FIG. 2;

FIG. 12 is an enlarged view of the encircled portion 12 in FIG. 4;

FIG. 13 is an enlarged view of the encircled portion 13 in FIG. 6;

FIG. 14 is an enlarged view of the encircled portion 14 in FIG. 6;

FIG. 15 is an enlarged view of the encircled portion 15 in FIG. 7; and,

FIG. 16 is an enlarged view of the encircled portion 16 in FIG. 8.

(Continued)

The dot-dash broken lines in FIGS. 1-2, 4, and 6-16 depict references to the enlarged views, indicate the locations from which corresponding enlarged views are taken, and form no part of the claimed design.

The remaining broken lines depict portions of the monitor that form no part of the claimed design.

1 Claim, 16 Drawing Sheets
